Joseph A. Ruff - Inventor

United States Patent Office.

JOSEPH A. RUFF, OF SOMERVILLE, MASSACHUSETTS, ASSIGNOR TO THE RUSSELL & ERWIN MANUFACTURING COMPANY, OF NEW BRITAIN, CONNECTICUT.

Design No. 3,826, dated January 25, 1870.

DESIGN FOR DOOR-ESCUTCHEON.

The Schedule referred to in these Letters Patent and making part of the same.

I, JOSEPH A. RUFF, of Somerville, in the county of Middlesex, and State of Massachusetts, have invented and produced a new and original Design for a Door-Escutcheon, of which the following is a specification.

The design shown in the accompanying photograph is surrounded by a raised moulding, *a*. The outlines are composed of curved and straight lines, which form angles and points, as shown. A ledge or moulding, *c*, also surrounds the knob-escutcheon *A*.

The face of the central projection *d* of the knob-escutcheon *A* is sexangular in form, and is surrounded by two circles of points, *e*, apparently one partially

over the other. The inner circle of points is ornamented by sunken channels.

The space surrounded by the moulding *a*, other than the knob-escutcheon *A*, is a ground of fine matted work, filled in with ornamental scroll-work in relief.

I claim, as my invention—

The ornamental design for a door-escutcheon, substantially as described, and shown in the accompanying photograph.

JOSEPH A. RUFF.
